US00D597671S

(12) **United States Design Patent**
Cottone, Jr. et al.

(10) **Patent No.:** **US D597,671 S**
(45) **Date of Patent:** **** Aug. 4, 2009**

(54) **POLYMERIC STENT STRUCTURE**

(75) Inventors: **Robert John Cottone, Jr.**, Davie, FL (US); **Shusheng Ye**, Miami, FL (US); **John Pazienza**, Pompano Beach, FL (US)

6,210,318 B1 4/2001 Lederman
6,348,065 B1 2/2002 Brown et al.
6,358,274 B1 3/2002 Thompson
6,432,132 B1 8/2002 Cottone et al.
6,471,719 B1 10/2002 Voinov et al.
6,488,703 B1 12/2002 Kveen et al.

(73) Assignee: **Orbusneich Medical, Inc.**, Ft. Lauderdale, FL (US)

(**) Term: **14 Years**

(21) Appl. No.: **29/249,795**

(22) Filed: **Oct. 20, 2006**

(51) **LOC (9) Cl.** **24-02**

(52) **U.S. Cl.** **D24/155**

(58) **Field of Classification Search** D24/155-157; 623/1.13-1.23; 604/1.02-103.02; D5/1-4, D5/47, 56, 99

DESCRIPTION

This application claims benefit from U.S. patent application Ser. No. 09/094,492, filed Jun. 10, 1998 now U.S. Pat. No. 6,117,165, issued Sep. 12, 2002; U.S. patent application Ser. No. 09/511,481, filed Feb. 23, 2000 now U.S. Pat. No. 7,108,714 issued Sep. 19, 2006; and U.S. patent application Ser. No. 10/014,705 filed Dec. 11, 2001, the disclosures of which are incorporated by reference herein in their entirety.

FIG. 1 is a top, front and right side perspective view of a polymeric stent structure showing our new design, the side opposite being a mirror image; and,

FIG. 2 is another top, front and right side perspective view thereof shown in fragment, on an enlarged scale, in a partially open condition.
